REFRIGERATING PORTABLE RECEPTACLE

Frank R. Kissling, Cleveland Heights, and
Edward R. Marbach, Cleveland, Ohio

Application July 13, 1933, Serial No. 680,262

9 Claims. (Cl. 62—91.5)

This invention relates to refrigerating receptacles, the principal object of which is to provide portable receptacles which are conveniently opened and closed, such as by a swinging cover for temporarily holding the contents of the receptacle therein, and especially by using a removable inner receptacle for such contents, the inner frame extending to a height such that means carried by the cover will contact such frame when the cover is closed.

Latching means is provided for the cover, and the receptacle is provided with handles pivoted at the ends of the main portion whereby the latter may be conveniently transferred over short distances manually while empty, or while filled with contents which may be carried by the inner receptacle, and may include in part or whole, bottles filled with liquid. A further advantage of our invention is the provision of a holder for a refrigeration material within the receptacle, and suspended from the cover.

It is a further object of our invention to provide said holder for refrigerating material, of telescopic parts which may be readily opened for filling as needed, and which holder may be detachably mounted on the cover of the receptacle, so that the opening of the cover makes the refrigerating holder conveniently accessible for refilling. This feature of the main structure of our improvement permits filling of the main receptacle, with contents such as liquid-filled bottles; and said main receptacle may remain so filled until delivery thereof is to be made where ordered, when opening the cover then permits filling said holder with a refrigerant, after which the cover is closed and latched.

With these and other objects in view, which will be revealed as our description proceeds, our invention consists in the novel combination and arrangement of parts set forth in the following specification and accompanying drawings in which:—

Figure 1 is an external front elevation of one of our portable receptacles;

Figure 2 is an end elevation of the same;

Figure 3 is a longitudinal section of such receptacle, taken in the plane indicated by the line 3—3 of Fig. 2, showing our preferred form and on an enlarged scale;

Figure 4 is a transverse view shown in the plane indicated by the line 4—4 of Fig. 3;

Figure 5 is a view similar to Fig. 4, but showing the cover partly raised;

Figure 6 is a section taken in a plane substan-

tially that of Fig. 3, but of a modified form of receptacle;

Figure 7 is a transverse sectional view of the form shown in Fig. 6 and in a plane indicated by the line 7—7 thereof, and on a larger scale;

Figure 8 is a perspective view of one of the telescopic parts of a holder detachably mountable on the cover of our receptacle and suspended from such cover, and

Figure 9 is a perspective view of a slidable part 10 of said holder.

In these drawings, the main receptacle is designated by numeral 5 of which 6 is the body member and 7 the cover member hinged thereto. These members may have walls formed of a heat insulating composition as an artificial board whose edges may be joined together by metal angle members 8, and cover 7 hinged at one edge upon an upper edge of a corresponding wall of the main body member 6. Suitable handles 10 are provided at the ends 9 of the chest, and the cover 7 is further provided with a latch 11 for securing the cover in closed relation. While such is the preferred material of the wall structure, it is not understood that our invention is by any means limited thereto, as our walls may be constructed of other materials while the refrigerating features of our invention may profitably be retained.

The recited heat insulating material may be braced for desired strength by frame members 12 adjacent the edges of the body faces and secured thereto, as will be understood. Certain enclosing members 12 of metal such as flat bands may be attached to the edges of the cover 7, as shown in Figs. 3 to 7 of the drawings, and protective in their character, especially for such top plate. To the inner surface of the cover 7 we may secure a polyhedral holder 13 comprising a pan-shaped member 14 having a perforated bottom 15, an open top from whose edges flanges are bent outwardly from its two side walls for attaching to the cover 7, the member 14 having one open end for receiving therein an inner pan 16 when the cover 7 is swung open. Bracing strips 29 of heat insulating material are attached to the cover as shown in Figs. 4 and 5.

The main body 6 of the receptacle 5 will ordinarily rest upon a horizontal support, both when the hinged cover 7 is swung open, and when latched at 11 serves to retain the cover closed upon said main body. The refrigerating holder 13 will in its telescopic relation be suspended from one end of the cover 7 at a point adjacent the cover hinges 11, as indicated in Fig. 4. In this

55

position the flanges 18 of the member 14 will take the position substantially level with the inner surface of the cover, and the depth of the pan 16 provided with the vertical walls 19, will be sufficiently shallow to be received in the member 14 telescopically, to be retained in such relation when the cover is closed as above explained.

The pan 16 can be easily filled with refrigerating material such as carbon-dioxide (CO₂)—often known by the popular term “dry ice”, especially effective in cooling the contents of the body 6 when the cover is closed. In assembling the holder 13, the filled pan 16 is inserted in the member 14 before closing the cover, and the perforations 20 of the bottom plate 15 gradually allow melting of the dioxide and flow of the resulting liquid from the bottom of the holder. This process will be very slow since the liquid flows from the inner pan down to the perforated bottom 15 before opportunity is afforded for outflow down into the receptacle itself.

While we have described the holder 13 as a telescopic and flat holder of small capacity, and referred to its adaptation for use with the material carbon-dioxide, in its solid form, as it will be clear that such solid may be molded to fit the pan 16, it is not to be understood that we are in any sense restricted to the use of this particular refrigerant material, designated in Fig. 4 by the numeral 21, but that other refrigerant materials may be filled into the pan 16.

It will now be understood that the main receptacle 5 is not only provided with insulating walls for protection from heat, but that it is especially desired to provide an inner metallic casing 22 having an open top and of suitable dimensions to conveniently and detachably be received into the outer walls of the main body 6, the said casing comprising a frame having a bottom 23 and upwardly bent walls 24 whose end walls will be provided with openings adjacent their top edges, to serve as hand holds 25 whereby, when the cover 7 is swung open, the casing 22 with its contents may be readily lifted out, and either filled or refilled, prior to being returned to the main body 6.

If it is desired to fill the main receptacle with bottles containing liquids, it has been found desirable to provide a suitable bracket 26 of the general outline of the transverse form of the casing in a plane parallel to the bottom of the latter, the edges of the bracket being suitably secured to the vertical walls of the casing and properly spaced from the bottom 23. Said bracket 26 will be provided with a desired number of openings 27, and which may be arranged in rows if desired, the several openings being of a size suitable for receiving therein the bottles to be stored while resting their weight upon the bottom 23. The depth of the casing 22 will be sufficient to receive the height of the bottle used.

It will be evident that the refrigerant structure for storing bottled liquids above described, adapts itself readily to moving such bottled stock while retaining the same in cool temperature, by the following means of manipulation. The casing 22 may be filled with bottles, if such is the stock to be retained cool, if desired to be so filled before lifting into the receptacle 6, and both the latter, as well as the case 22, cooled before the holder 13 is filled with the refrigerant contents 21 for immediate cooling.

Our novel structure thus enables a plurality of cases 22 filled with bottles to be cooled ready for loading in the main case 6. It is also feasible

to cool the main case interiorly before filling the metal case 22, the holder 13 being inserted last before closing and latching the cover 7. The case 22 being filled with bottles positioned in the bracket 26, is set in the main case 6 by grasping the handles 25, after which the holder 13 is filled with the refrigerant 21. As the cover is then closed, the supporting strips 29 will rest upon the inner case 22 at the point 32, in the preferred form, in Figs. 1 to 5; the advantageous pressure 10 exerted by the cover in closing against the case 22 prevents undesirable movement of the latter as will be evident.

Very little weight is added to the case holding the stock enclosed, by the use of the holder 13 15 as described, while effectively maintaining the low temperature of the contents of such case 22, and for long periods of time after filling the same. A suitable choice of heat insulating material for the walls of the main case 6 is afforded, and little 20 disadvantage has been found to result from the use of metal for the inner case 22 as described.

It will be obvious that an exceedingly large stock of bottles sealed and holding cooled liquids ready for transportation by any of the more ordinary means may be stored in very large chambers filled to their approximate capacity without wasting much refrigerating material, and that our structure here disclosed may make possible filling such casing, when required promptly with the 30 cold stock, after which the cover, with its filled holder 13 is closed, and the case is ready for shipment.

It is an advantage in some uses of our structure that the inner telescopic pan 16 is removable from the outer part 14, as shown in our preferred form in Figs. 1, 2, 3, 4, 5, 8, and 9, in a direction lengthwise of the cover 7 and receptacle 5. We however have uses for applying the containers or holders 13 transverse of the chest 40 and cover, in the manner shown in Figs. 6 and 7 of the drawings which provide a modified form showing a mounting of the holder whose side walls are suspended from the flanges 18 which are secured to the inner surface of the cover 7, and 45 transverse of the latter, and whereby the length of the closed holder 13 fits quite aptly between the side walls of the main body 6, when the cover 7 with its holder 13 is closed.

In either form of our complete receptacle 5, 50 the same general form of telescopic members 14 and 16 will be used, it being understood however that the relative length of the closed holder 13 to the top opening of the body member 6, as well as to the size and general outline of the cover 7, will remain substantially in the preferred form of Figs. 3, 4 and 5, in a plane at right angles to the relative position of such holder in the modified form of Figs. 6 and 7.

In either structural form however the open end of the member 16 will be limited in its movement by contact with the closed end 28 of member 14, so that a cavity results which is closed by their telescopic relation, the bottom openings 20 serving the only means of air circulation from the contents of the pan 16 and the interior of the main chest 22. In the preferred form of refrigerant holder 13, it is often found advantageous to support the flanges 18 of the member 14 upon supporting strips 29 of the cover, as shown in Figs. 3, 4 and 5. In the latter case, the length of the holder 13 will be approximately one half that of the main chest or cover.

The supports 30 of Figs. 6 and 7 rest upon 75

case 22 at point 31, and supports 29 rest upon 22 in Figs. 3, 4 and 5, at point 32.

It is to be understood that other changes in construction may be made as may prove expedient and fall within the scope of the appended claims.

Having described our invention, what we claim and desire to secure by Letters Patent, is:—

1. A portable refrigerating receptacle including the combination of a container having heat insulated walls, means exterior thereof for manually moving the receptacle and a cover hingedly attachable to the upper edge of one of said walls and having a latch for detachably securing the cover closed, a refrigerant holder comprising telescopically slideable metal members for supporting refrigerant material, the outer member being supported from the inner surface of said cover, the length of said holder being substantially identical with the width of the inner dimension of said insulated container, and a holding container for articles to be cooled, insertable from above into said insulated container when the cover is open.
2. A portable refrigerating receptacle including the combination of a container having heat insulated walls, means exterior thereof for manually moving the receptacle and a cover hingedly attachable to the upper edge of one of said walls and having a latch for detachably securing the cover closed, a holder comprising telescopically slideable metal members for supporting a piece of dry ice therein, the outer member being supported upon the inner surface of said cover, a metal container for holding the articles to be cooled readily insertable within said first container and having handle slots at the ends for manually moving said metal container with the articles to be cooled, and the bottom of the outer member of said holder being perforated to permit circulation of refrigerating air through said telescopic holder.
3. A refrigerating receptacle including a container having heat insulated walls, a cover hingedly mounted on the upper edge of one of said walls and having a latch for detachably securing the cover closed, a refrigerant holder comprising telescopic metal members for supporting a piece of dry ice, the outer member being supported upon the inner surface of said cover, an inner container for readily holding bottles to be cooled, insertable within said container having heat insulated walls, said inner container having a guiding bracket mounted within the latter container spaced from the bottom and perforated to receive the bottle necks therethrough, and the outer member of said refrigerant holder being perforated to permit circulation of refrigerating air through said telescopic holder.
4. A portable refrigerating receptacle including the combination of a container having imperforate insulating walls and an open top, a swinging cover hingedly attachable to an upper edge of one of said walls and having a latch for detachably securing the cover closed, a holder comprising telescopic metal parts for supporting refrigerant material therein, the outer part being secured upon the inner surface of said cover and its bottom being perforated, the inner part directly supporting the refrigerant, the length of said holder being of adequate extent to rest between the side walls of the insulated container when the cover is closed, an inner container for holding beverage bottles to be cooled, insertable
5. A refrigerating receptacle including a container having a heat insulated bottom and vertical walls and an open top, a cover hingedly mounted on the upper edge of one of said walls, a holder comprising telescopic members for supporting a piece of dry ice therein, the outer member having flanges for attachment to the inner surface of said cover, and a perforated bottom to permit circulation of refrigerating air through said holder, a supporting container for holding bottles to be cooled, insertable within the heat insulated container, the said supporting container having a guiding bracket mounted within the same, spaced from the bottom and perforated to hold the bottles suitably spaced.
6. A portable refrigerating receptacle comprising a case having an open top and heat insulating walls, means exterior thereof for manually moving the case and a cover hingedly mounted on the upper edge of one of said walls, a latch for fastening the cover in closed position, a refrigerant holder comprising telescopically slideable members for supporting a piece of dry ice, the outer member being supported upon the inner surface of said cover and having a perforated bottom to permit circulation between the ice cavity and the interior of the main receptacle, and the dimensions of said holder permitting lowering thereof into said interior when the cover is closed.
7. A portable refrigerating receptacle including the combination of a case having imperforate insulating walls and an open top, a cover hingedly mounted on the upper edge of one of said walls and having a latch for detachably securing the cover closed, a hollow flat holder comprising telescopic metal members for supporting therein a molded refrigerant, the outer member having flanges for attachment to the inner surface of said cover and having a perforated bottom to permit circulation between the refrigerant cavity and the interior of said main case, the inner member directly supporting the refrigerant therein and removable from the outer member for filling with the refrigerant, when the cover is raised, and the depth of the holder being adequately shallow to permit closing the cover without contacting the contents of the interior of the main cavity of the case.
8. A portable refrigerating receptacle including the combination of a case having imperforate insulating walls and an open top, a cover hingedly mounted on the upper edge of one of said walls and having a latch for detachably securing the cover closed, an inner container for readily holding bottles to be cooled, insertable within said first-mentioned container, said inner container having a guiding bracket mounted within the latter, spaced from the bottom and perforated to receive the bottle necks therethrough, the upper edges of said inner container being in contact with the inner adjacent surface of said cover when closed, and means detachably mounted on the inner surface of said cover for receiving therein a refrigerant material.
9. A refrigerating receptacle including a container having imperforate heat insulating walls and an open top, an imperforate cover hingedly mounted on the upper edge of one of said walls and having means for detachably securing the cover closed, a holder comprising telescopic members for supporting therein refrigerating material, the

outer part being secured upon the inner surface of said cover and its bottom being perforated to permit circulation of refrigerating air through the holder, and the inner member directly supporting the refrigerant, and the length of said holder being adequate to enter between the side

walls of the insulated container when the cover is closed without contacting the contents of the container.

FRANK R. KISSLING.
